CLAIM

The ornamental design for a jug, as shown and described.

DESCRIPTION

FIG. 1 is a top, front, left perspective view of a jug showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The pairs of jagged broken lines are shown broken away to disclose indeterminate length, and the portions of the design that may be visible between such jagged lines have been removed for clarity. The remaining even-length broken lines are directed to environment only and do not form part of the claimed design.
